UNITED STATES PATENT OFFICE.

ARTHUR HOMER DAUCHY, OF SAN DIEGO, CALIFORNIA.

VALVE AND FAUCET.

SPECIFICATION forming part of Letters Patent No. 433,198, dated July 29, 1890.

Application filed February 6, 1890. Serial No. 339,501. (No model.)

To all whom it may concern:

Be it known that I, ARTHUR HOMER DAUCHY, a citizen of the United States, and a resident of San Diego, in the county of San Diego and State of California, have invented certain new and useful Improvements in Valves and Faucets for Extracting Fluids from Cans, Barrels, Bottles, &c., of which the following is a specification.

10 The object of my invention is to provide a simple and efficient device by which the liquid contents of a can, barrel, bottle, or other vessel may be readily drawn therefrom when so desired, and which will be so constructed as 15 to entirely close the can and permit the removal of the faucet when the liquid is not being withdrawn. This object I accomplish by the use of the device shown in the accompanying drawings; and the invention consists 20 in certain novel features of the same, as will be hereinafter described and pointed out.

In the drawings referred to, Figure 1 is a perspective view of an oil-can having my improved device applied thereto. Fig. 2 is a 25 longitudinal section of the faucet. Fig. 3 is a longitudinal section of the valve. Fig. 4 is a view of a washer or ring at the inner end of the valve-cylinder. Fig. 5 is a view showing the valve-cylinder in a side and end elevation. Fig. 6 is a view of the spring which 30 holds the valve normally closed. Fig. 7 is a side view of the valve. Fig. 8 is a side view of the valve-seat and support for the faucet. Fig. 9 is a front view of the valve-seat, and 35 Figs. 10 and 11 are detail views showing a modified construction of the front end of the valve-seat.

Referring to the drawings by letter, P designates the can, which may be of the usual or 40 any preferred construction and is provided with an opening at a proper point of one of its walls for the insertion of the valve-cylinder, as shown most clearly in Fig. 3.

The valve-cylinder A is constructed of sheet 45 metal rolled into the proper form and provided at its inner end with a series of projections or teeth B, which are bent inward, as shown most clearly in Fig. 5, so as to form a rest for the ring or stop C, which is provided with a central opening in which the 50 stem I of the valve is mounted. The cylinder

A is also provided with a series of openings D, through which the liquid contents of the vessel pass into the cylinder, and the valve K is normally projected forward and in advance of these perforations D by the spring J, which is arranged around the valve between the valve and the ring C.

The valve is provided on its outer or front face with the cushion L, formed of rubber, leather, or other suitable similar material, and adapted to rest against the rear side of the valve-seat E and form a tight joint, so as to prevent the leakage of the liquid.

The valve-seat consists of a cylinder E, having an annular flange H at its outer end, which is adapted to rest against the outer side of the can and be secured thereto, and provided at its inner end with an annular shoulder or collar F, which rests against the inner surface of the cylinder A and forms a tight joint therewith. A hollow conical support G is secured concentrically within the cylinder E and forms a rest for the faucet when the device is in use.

M designates the faucet, which consists of an approximately L-shaped tube having a projection O on its upper side which serves as a thumb-rest, and provided in its interior with a bracket-tube, in which and the front 80 wall at the faucet a sliding key or plug N is mounted.

In practice when it is desired to extract some of the contents of the vessel, the end of the faucet is inserted in the cylinder E and 85 over the support G, after which the key N is pushed through the said support G against the valve, and the valve thereby forced rearward, so as to permit the liquid to pass through the perforations D and the support G into 90 the faucet and thence to any suitable receptacle. After the desired quantity of liquid has been withdrawn the key N is drawn forward and the faucet removed, when the valve is automatically thrown against the valve-seat, so as to cut off the flow of liquid by the spring J, as will be readily understood.

In Figs. 10 and 11 I have shown the flange H as provided with vertical faces having the guiding ribs or cleats I, in which a vertically- 100 sliding gate J is mounted. This gate is adapted, when the device is not in use, to be

pushed downward, so as to close the opening in the valve-seat, and consequently prevent dirt collecting on the same and also prevent insects passing into the valve-cylinder. The 5 vertical movement of the gate is limited by a teat L, formed on the outer side of the flange and engaging a groove K in the gate, as clearly shown.

My improved device is very simple in its 10 construction and efficient in its operation.

The several parts are compactly arranged and the advantages of the device are thought to be obvious.

Having thus described my invention, what 15 I claim, and desire to secure by Letters Patent, is—

The combination of the valve-cylinder, the valve-seat secured in the front end of the cylinder and provided with an internal concentric faucet-support, the valve arranged in the cylinder in rear of the valve-seat and held normally against the valve-seat, and the faucet removably fitted on the faucet-support and carrying a sliding key adapted to pass through the support and push the valve from 20 its seat, as specified.

In witness whereof I have hereunto set my hand and seal.

ARTHUR HOMER DAUCHY. [L.S.]
